SPENCER LEWIS, OF TIFFIN, OHIO.

Letters Patent No. 71,395, dated November 26, 1867.

IMPROVED FLOUR-BOLT.

The Schedule referred to in these Letters Patent and making part of the same.

TO ALL WHOM IT MAY CONCERN:

Be it known that I, SPENCER LEWIS, of Tiffin, in the county of Seneca, and State of Ohio, have invented an improved Flour-Bolt; and I do hereby declare the following to be a full, clear, and exact description thereof, reference being had to the accompanying drawings, making part of this specification, in which—

Figure 1 is a longitudinal section through the improved bolt, taken in the vertical planes indicated by the course of the red line yy in fig. 2.

Figure 2 is a transverse section taken through the bolt in the vertical plane indicated by red line zz in fig. 1.

Figure 3 is an enlarged view in detail, showing more particularly the construction of one of the knockers and the cam which operates it.

Similar letters of reference indicate corresponding parts in the several figures.

The object of this invention and improvement in flour-bolts is to provide for obtaining different grades of flour without changing the external bolting-cloth, by the application of a cloth to the interior of the reel, part of which is very coarse, and part very fine, and arranging within that portion of the exterior cloth, which is coarsest, a very fine cloth, which is applied to an adjustable frame, and so arranged that it can be adjusted toward or from that end of the bolt in which the flour is fed, as will be hereinafter described.

Another object of my invention is to provide for shaking or jarring the ribs and cloth of a flour-bolt, so as to facilitate the passage of the flour through it, by means of hammers, longitudinally movable spring-rods, and applied to the ribs of the bolt within the bolting-cloth, and adjustable cam-plate applied on the inside of the bolt-chest, as will be hereinafter described.

To enable others skilled in the art to understand my invention, I will describe its construction and operation.

In the accompanying drawings, A represents the bolting-chest, within which is arranged, in an inclined plane, the rotating bolt. The bolting-reel or frame consists of head-pieces, B and C, to which are secured the longitudinal bars or ribs D D, that are connected at suitable points to a longitudinal shaft, E, passing through the centre of the reel, by means of radial arms or braces E', as shown in figs. 1 and 2. The shaft E has its end bearings in the ends of the chest A, and the upper or highest end of this shaft passes through the chest and is driven by means applied outside of the chest, in any suitable manner. Surrounding the reel thus described are two cloths, a b , of different degrees of fineness. The cloth a is the coarsest, and occupies about one-fourth the length of the reel, more or less, and it is suitably united to the fine cloth b , which should be sufficiently fine to make the best merchantable flour, while the coarse cloth gives what is termed custom-flour. Within the space surrounded by the coarse cloth a , at or near the upper end of the reel, is a cloth b' , corresponding in length to this external cloth a , and, in fineness, to the cloth b . This internal cloth b' is stretched around short pieces, D', which are placed in longitudinal slots in the longitudinal ribs D, and secured to a ring, F, as shown in figs. 1 and 2. The pieces D' are shorter than the slots in which they are fitted, so that they may all be moved in a direction with the length of the reel, by means of the rod G which is attached to the ring F, and extended nearly to the discharging-end of this reel, as shown in fig. 1.

By moving this internal-cloth frame toward the upper end or head of the reel, so as to entirely cover the external coarser cloth a , a fine bolting-cloth through the entire length of the bolt will be obtained, thus making a perfect "merchant-bolt," and by drawing the interior cloth from the head of the reel, a coarser grade of flour will be obtained. By adjusting this internal cloth so as to allow more or less of the flour to pass over and through the external cloth a , any desired grade of flour may be obtained.

Upon two of the longitudinal ribs D of the reel, inside of the external bolting-cloth, I have applied hammers or knockers, for striking upon the ribs as the reel is revolved, and thus jarring this reel, and causing the flour to pass more freely through the bolting-cloth or cloths. As both hammers are constructed and operated alike, I will describe but one of them, together with the mode of actuating them.

The hammer g is secured to a short shaft, having its bearings in a standard, g' , and having a crank, h , at one end. This crank h enters an oblong slot, which is made through an arm, h' , secured upon a longitudinal sliding rod, J, so that, by moving this rod endwise, the hammer can be vibrated and caused to strike the rib to which it is pivoted. The rod J passes through eye-bearings i fastened to the rib of the reel, and carries on its outer end a small anti-friction roller, j , shown in figs. 1 and 3. A strong spring, k , is coiled around the rod J,

and so applied to it that, when this rod is suddenly released, after having raised the hammer *g*, the latter will be caused to strike a smart blow upon its rib *D*, or upon a metal plate inserted therein to protect the rib from rapidly wearing out.

For the purpose of forcing back the rods *J* *J*, and then suddenly releasing them, I employ a segmental cam-plate, *S*, which is secured at one end to the end of the chest *A*, inside thereof, and supported in position by means of a screw, *p*, which is secured into the chest *A*, and provided with a circular turning-nut or head, *r*, upon it.

This cam-plate is thus applied to the chest for the purpose of allowing a person to regulate the force of the blows of the hammers, or to stop the action of these hammers altogether. To effect this a cord, *N*, (see figs. 1 and 2,) passes over the grooved head *r* of the screw *p*, and down through the bottom of the bolt-chest. By means of this cord the screw *p* can be turned, either to the right or left, and the lower end of the cam-plate set further from or nearer to the end of the chest to which this plate is secured. The anti-friction wheels *j*, on the outer ends of the hammer-rods *J*, are alternately brought in contact with the surface of the cam-plate *S*, as the reel is rotated, and the hammers are caused to strike with greater or less force, according to the length of movement given to the hammer-rods by said cam-plate, which can be adjusted as described.

Having described my invention, what I claim as new, and desire to secure by Letters Patent, is—

1. A bolting-cloth applied to a sliding frame, and arranged within a bolting-reel, which is covered with bolting-cloth of different degrees of fineness, for producing different grades of flour at pleasure, substantially as described.

2. The hammers *g*, secured to crank-shafts, the cranked ends of which play in slotted arms *h*', upon longitudinally sliding spring-rods *J*, in combination with an adjustable cam-plate, *S*, upon the inside of the bolting-chest, all constructed, arranged, and operating substantially as described.

3. The adjustable screw-pulley *r* applied upon a stud, *p*, and provided with cord *N*, for adjusting the cam-plate *S*, substantially as described.

S. LEWIS.
